UNITED STATES PATENT OFFICE

THOMAS HARDIE SEAY, OF WASHINGTON, DISTRICT OF COLUMBIA

FILE CABINET AND SHIPPING CASE

Application filed December 10, 1928. Serial No. 325,074.

Generically this invention relates to containers, but it is more especially directed to a type adaptable as a file cabinet and as a shipping case.

5 An important object of this invention is the provision of a combination file cabinet and shipping case comprising a hinged side, initially adaptable as a file cabinet and when containing the requisite files adaptable as a 10 shipping case, said container comprising means for expeditiously securing the filed contents and preventing mutilation or disarrangement thereof during course of shipping.

15 A still further object of this invention is the provision of a container having a movable side, one side of said container having means adapted to adjustably receive one edge of a plate and similar means carried by 20 the movable side adapted to adjustably engage the opposite edge of the plate when the side is brought to operative position to firmly lock and maintain said plate in pressing contact with the files to prevent their disarrangement during course of handling, irrespective of the quantity thereof, and means 25 for expeditiously securing the top to the container, said securing means at the same time constituting a handle for said container.

20 With these and other objects in view, which will become apparent as the description proceeds, the invention resides in the construction, combination and arrangement of parts, hereinafter more fully described 35 and claimed, and illustrated in the accompanying drawings, in which like characters of reference indicate like parts throughout the several figures, of which:

40 Fig. 1 is a perspective view of the container in open position in readiness to receive the files or other contents;

Fig. 2 is a cross section of Fig. 1 when the device is being employed as a shipping case;

45 Fig. 3 is a view in elevation of the top showing tag holder;

Fig. 4 is a cross section of the top and tag holder;

Fig. 5 is a cross section of one of the anchoring means.

Fig. 6 is a cross section taken on the line 6—6 of Fig. 5; and

Fig. 7 is a cross section taken on the line 7—7 of Fig. 5.

While I am aware that there are various 55 types of containers, shipping crates and the like, insofar as I am aware they are not susceptible of expeditious use as both a filing cabinet and shipping case, especially in connection with the handling of interline accounts between the various railroad systems. During each month account sheets with allied systems are built up and at the end of each month it is necessary to forward such files to the various railway accounting offices, and at the present time, it is prevalent to fold and tie these files in bundles for shipment during the course of which they become mutilated, disarranged and by reason of having been folded difficult to properly handle, requiring great labor and expense to arrange for final audit; and it was to overcome the inherent disadvantages of such a system and to provide a container utilizable throughout a given period as a file cabinet and thereafter 70 without additional handling of the file contents, as a shipping case, and comprising an adjustable means for expeditiously securing and maintaining the said files in their original shape and arrangement, irrespective of the quantity within the container and so maintain them in their original condition and arrangement during such shipment, that I designed the combination file cabinet and shipping case forming the subject matter of 75 this invention.

In the illustrated embodiment characterizing this invention there is shown a container "A" in the present instance of substantially rectangular configuration, comprising bottom 1, end walls 2 and 3 and side walls 4 and 5, respectively. While the side 4 is formed integral with the ends 2 and 3, the side 5 is hinged along its lower edge to bottom 1 by a piano hinge or in any well known manner for a purpose hereinafter more fully understood.

Suitably secured by spot welding or otherwise as at 6 to the inner surface of side 4 spaced from each end is an anchor member 105

B formed with flanges 7 and ridge portion 8 formed with a plurality of spaced transverse slots 9 throughout its length, such slots adapted to align with those of a corresponding pair of members B are similarly positioned and secured to the inner surface of movable side 5, the slots of the respective members adapted to align when the side 5 is in an upright or contacting position with the ends 2 and 3, for a purpose hereinafter more fully apparent.

The container is provided with a movable closure or top 11 formed with a flange 12, the lower edge of said flange being folded inwardly upon itself as at 13 to form a thickened edge, said flange adapted to overlie the sides and end portions. Spot welded or otherwise suitably secured to the outer surface of end 2 adjacent its upper edge as at 14 is plate 15 hingedly supporting a loop member 16, and suitably secured to the free end of said loop is strap 17, in the present instance, provided with buckle 18 and similar members 15 and 16 are correspondingly positioned and secured to the outer surface of end 3 carrying strap member 19 adapted to engage buckle 18 when the top 11 has been operatively positioned over the container to secure said top and to provide a handle by means of which the container may be transported during course of handling.

In order to further strengthen the container when being used as a shipping case the side 5 is provided adjacent each of its outer corners with a lip projection 20 for engagement with the inner surfaces of the respective end portions 2 and 3 to provide a bracing means therefor.

When the files have been suitably positioned in the container and it is desired to secure them against movement during handling of said container, one edge of a board or plate 22 preferably formed of fiber or other suitable material is adapted to be inserted in slots 9 of members B secured to the side 4 slightly below the normal surface of the file contents, the free edge being pressed downwardly and inserted in the corresponding aligned slots in the members B of side 5 as they are brought into engagement with the free edge of said board, so that when said side reaches a vertical position the board will be firmly located in pressing contact with the file contents not only preventing any disarrangement thereof but insuring their delivery at point of destination in their original condition, and while the container may be constructed of any desired material I have preferably shown it as constructed from sheet metal and so constructed as to withstand long and continued hard usage.

In order to facilitate tagging of the device when employed as a shipping crate the top 11 is formed with an opening 23 and underlying the opening is a pan like holder

24 suitably secured to the under surface of the top surrounding said opening with one end open, and suitable secured to the bottom of said holder member 24 as at 25 is a leaf spring 26 having a catch portion 27 adapted to extend across said open end of the holder member and contact the under surface of the top to retain therein a detachable tag of conventional design bearing the desired address, the said opening 23 being suitably closed by a glass or other transparent element not shown.

From the above it is apparent that I have designed a combination device of great utility and adaptability, capable of effecting a great saving in time and labor as well as protection to the files by constituting in the first instance an efficient file cabinet, and in the second, a shipping case for such files without the necessity of their rearrangement or additional handling and preserving them in their original condition, thereby not only preserving the files themselves but eliminating a number of handling operations intermediate the lines of origin and those of final destination, yet one simple in construction, manufacturable at a negligible cost, susceptible of repeated and continued hard usage and efficient for the purposes intended.

While my invention is peculiarly adaptable for the shipment of the interline accounts between various railroads it is equally as adaptable to other uses, as will be apparent without further explanation.

Although in practice I have found that the form of my invention illustrated in the accompanying drawings and referred to in the above description as the preferred embodiment, is the most efficient and practical; yet realizing the conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. A container constituting a combination file cabinet and shipping case, comprising a movable side, a pair of slotted ridge members secured to said movable side, and a pair to the opposite side, a compression plate selectively engageable with certain slots of one pair and with corresponding slots of the pair on the movable member when the same is in closed position, a closure for said container, an auxiliary tag holding receptacle carried by said closure, and means for securing the closure on the container, whereby the container initially serves as a file cabinet and when the contents have been locked against displacement and

the closure secured therein, the same constitutes a complete shipping cabinet with an address tag secured therein.

2. A container constituting a combination file cabinet and shipping case, comprising a hinged side, lip projections formed on said side adapted to engage the inner surfaces of the respective sides of the container to brace the same, a pair of spaced vertical ridge members secured to said hinged side and a pair to the opposite side, each of said members being formed with a plurality of transverse slots, a compression plate selectively engageable with corresponding slots of said pairs, when said hinged side is in closed position, a removable closure for said container having a cut out portion, a tag holding means underlying said opening, a spring catch carried by the holding means and coacting with said closure, and means carried by the container for securing the closure thereto and constituting a handle, whereby the container successively constitutes a file cabinet and shipping case, with its contents and address tag, respectively, secured against displacement.
